VARIABLE STROKE MOTOR

Donald M. Berges, Tenafly, N. J., assignor to
 Bendix Aviation Corporation, South Bend, Ind.,
 a corporation of Delaware

Application April 18, 1941, Serial No. 389,253

3 Claims. (Cl. 121—150)

This invention relates to hydraulic motors, and more particularly to a reciprocating motor having a variable stroke.

It is an object of the present invention to provide a hydraulic motor wherein the direction of the working stroke may be automatically reversed upon the increase of pressure beyond a predetermined value.

Other objects of the invention include the provision of a hydraulic motor wherein the working stroke may be reversed at any time prior to its normal complete stroke upon the encountering of an obstruction, and the provision of a hydraulic motor wherein the presence of an obstruction during the normal working stroke automatically limits and effects the reversal of the working stroke.

Other objects will appear from a study of the following specification when made in conjunction with the attached drawing, wherein the single figure of the drawing is an elevational view, partly in section, of one embodiment of the present invention.

A motor housing 10 of cast steel, aluminum or other suitable material, contains a double ended cylinder 11 having a fluid port 12 at one end and a second fluid port 13 at the other end thereof. A working piston 14, of any suitable design, is mounted for reciprocal movement within cylinder 11 and has attached thereto a piston rod 15, which may be connected to any suitable device such as a windshield wiper, designated generally as 16. Immediately below cylinder 11 there is a valve chamber 17 containing valve members 18 and 19 rigidly attached to a valve rod 20, which has ends extended through valve members 18 and 19, and terminating in enlarged head members 21 and 22.

Auxiliary piston members 23 and 24 are slidably carried on piston rod 20 and spaced from valve members 18 and 19 by means of coiled springs 25 and 26, respectively. Outward motion of auxiliary pistons 23 and 24 along valve rod 20 is limited by the head members 21 and 22. The bottom portion of the periphery of valve member 18 contains a small indentation 27, and a corresponding indentation 28 is formed in valve member 19. Also, for cooperation with these indentations, detent members 29 and 30 are placed within recesses in motor housing 10. These detents may be of any conventional type such as the spring-loaded balls indicated in the drawing.

Oil or other fluid under pressure from a source such as pump 31 is carried through conduit 32 into valve chamber 17 and may be admitted to

cylinder 11 through either of the ports or passageways 33 and 34. As shown in the drawing, passageway 33 is open to cylinder 11, and oil will be admitted through this passageway into cylinder 11. Relief outlets or exhaust ports 35 and 36 are afforded for the return of oil through conduits 37 and 38 to a sump 39.

The operation of the hydraulic motor shown will be readily understood. Oil under pressure flows from pump 31 through conduit 32 and into cylinder 11 through passageway 33, forcing piston 14 to the extreme right of cylinder 11. When piston 14 reaches the end of its right-hand travel, continued flow of oil from pump 31 results in a greatly increased pressure on the left side of cylinder 11, and this pressure is transmitted through fluid port 12 to the face of auxiliary piston 23, forcing this piston to compress spring 25. This spring (as well as spring 26) has a pre-selected resilient value so that upon compression by movement of piston 23, the restraining force of detent 29 is overcome, and valve 18 is released with a snap action to close off passageway 33 from oil inlet 32. This movement of valve 18 carries indentation 28 of valve 18 into engagement with detent 30, and also carries the end face 22 of the valve rod against the inside wall of housing 10. In this position, oil flows into cylinder 11 through passageway 34, causing piston 14 to move to the left until it abuts with the internal end wall of cylinder 11. As pump 31 continues to function, and attempts to pump additional oil through passageway 34, the pressure of oil upon the face of auxiliary piston 24 increases, causing spring 26 to be compressed, and eventually, upon sufficient compression, causing valve 19 to be released from the restraining influence of detent 30, so that, with the snap action imparted by compressed spring 26, valve 18 is again forced into engagement with detent 29, as shown in the drawing.

The starting and stopping of the motor which is the subject of the present invention may be controlled by any suitable valve system. In the drawing, a two-way valve 40, having a handle 41, may be provided. As shown, valve 40 has a passageway 42 which, in the position illustrated, permits pressure from pump 31 to be imparted to the motor through intake conduit 32. If it is desired to stop the operation of the motor, handle 41 may be turned so that a second passageway 43 places the output of the pump 31 in communication with a by-pass conduit 44 through the bottom portion of conduit 32. With valve 40 in this position, pump 31 returns oil in its output to the sump 39, by way of exhaust conduit 37.

Thus, when the motor of the present invention is not in operation, the pump 31, which is the source of operating pressure, may continue to pump oil under light load, and yet be instantaneously available for the operation of the hydraulic motor.

While the hydraulic motor shown and described has general application, it is particularly useful in the actuation of an aircraft windshield wiper, principally since the accumulation of ice or any other obstruction encountered in flight which tends to limit the full stroke of piston 14 does not prevent the continued use of the motor to drive the windshield wiper through a path of shortened stroke. For example, if we assume that piston 14, at the position shown in the drawing, is prevented from moving further to the right by the formation of ice on the windshield of an airplane, the increase of hydraulic pressure against the face of piston 23 will cause a reversal of fluid flow in the manner above described so that the windshield wiper 16 may still be used to clean a restricted portion of the windshield.

The use of the motor of the present invention to drive a windshield wiper is to be taken as only one example of the possible applications to which the invention may be put. The invention is to be limited, therefore, not by the particular embodiment shown and described, but by the scope of the appended claims.

I claim:

1. In a hydraulic motor including a piston having a working stroke in two directions of travel, valve means for permitting the travel of said piston in each direction and for reversing the direction of travel of said piston, said valve means including a valve rod, two spaced valve members fixed to said rod, two auxiliary piston members slidably carried by said valve rod and maintained resiliently spaced from said valve members, a valve and piston chamber enclosing said valve members and auxiliary pistons, detent means for selectively holding one of said valve members in a fixed position, and fluid ports opening on opposite sides of said pistons, whereby, upon the increase of fluid pressure beyond a pre-

determined value, said auxiliary pistons will be selectively urged toward its corresponding valve member with a force sufficient to free said valve member from said detent and move it to reverse the direction of fluid flow against said piston.

2. In a hydraulic motor including a piston having a working stroke in two directions of travel, valve means for permitting the travel of said piston in each direction and for reversing the direction of travel of said piston, said valve means including a valve rod, a valve member fixed to said rod, an auxiliary piston member slidably carried by said valve rod and maintained resiliently spaced from said valve member, a chamber enclosing said valve and auxiliary piston means, detent means for holding said valve member in a fixed position, and a fluid port open to said piston and to said auxiliary piston, whereby, upon the increase of fluid pressure beyond a predetermined value, said auxiliary piston will be urged toward said valve member with a force sufficient to free said valve member from said detent and move it to change the direction of fluid flow with respect to said piston.
3. A hydraulic motor comprising a housing, a double-ended cylinder within said housing, a working piston, a piston rod connected thereto, a fluid port at each end of said cylinder, a valve chamber in said housing, a valve member associated with each of said ports, a source of fluid pressure connected to said housing, relief ports in said chamber, a valve rod rigidly connected to said valve members, an auxiliary piston slidably carried on said valve rod and movable in said valve chamber, a passageway between each end of said cylinder and one face of each of said auxiliary pistons, means for resiliently spacing each of said auxiliary pistons from said valve members, said auxiliary pistons being movable toward said valve members under increasing pressure as said working piston is performing work, and means subject to the increase of pressure beyond a predetermined limit for causing said valves to reverse the flow of fluid through said ports into said cylinder.

DONALD M. BERGES.
